UNITED STATES PATENT OFFICE

ALVIN G. SHERMAN, OF DETROIT, MICHIGAN, ASSIGNOR TO THE DETROIT VAPOR STOVE COMPANY, OF DETROIT, MICHIGAN, A CORPORATION OF MICHIGAN

DESIGN FOR A COMBINED MANIFOLD COVER AND BURNER BOX

Application filed November 7, 1929. Serial No. 33,361. Term of patent 7 years.

To all whom it may concern:

Be it known that I, ALVIN G. SHERMAN, a citizen of the United States, residing at 216 Lakeland Avenue, Detroit, in the county of Wayne and State of Michigan, have invented a new, original, and ornamental Design for a Combined Manifold Cover and Burner Box, of which the following is a specification, reference being made to the accompanying drawings, forming part thereof.

Fig. 1 is a front perspective view of the

combined manifold cover and burner box, showing my new design;

Fig. 2 is a front elevation of the manifold cover detached from the burner box; and

Fig. 3 is an end elevation of the manifold cover shown in Fig. 2.

I claim:

The ornamental design for a combined manifold cover and burner box as shown.

ALVIN G. SHERMAN.
